CABINET SINK

Sheldon M. Rutter, Lake Forest, Ill., assignor to Acme Steel Company, Chicago, Ill., a corporation of Illinois

Application June 19, 1956, Serial No. 41,975

Term of patent 14 years

(Cl. D4—2)

Fig. 2.

Fig. 3.

Fig. 4.

Figure 1 is a perspective view of a cabinet sink, showing my new design;

Figure 2 shows a vertical section taken on the line 2-2 of Figure 1;

Figure 3 shows an enlarged top plan view of the middle portion of the sink top shown in Figure 1; and

Figure 4 shows a front elevation of the portion of the sink top which is illustrated in Figure 3.

The essential features of the design reside in the sink top shown in full lines in the drawings. The broken lines merely represent one environment in which the sink may be employed.

I claim:

The ornamental design for a cabinet sink, as shown and described.
